UNITED STATES PATENT OFFICE.

WILLIAM E. HENDERSON, OF IRON MOUNTAIN, MISSOURI.

CARPET-STRETCHER.

SPECIFICATION forming part of Letters Patent No. 256,838, dated April 25, 1882.

Application filed December 20, 1881. (No model.)

To all whom it may concern:

Be it known that I, WILLIAM E. HENDERSON, of Iron Mountain, Missouri, have made a new and useful Improvement in Carpet-Stretchers, of which the following is a full, clear, and exact description, reference being had to the annexed drawings, making part of this specification, in which—

Figure 1 is a view in perspective of the improved stretcher; Fig. 2, a view in perspective from the under side of the stretcher-plate; Fig. 3, a view in perspective, looking toward the under side of the crab; Fig. 4, a side elevation of the stretcher-plate as in use, the plate being pressed downward and the carpet being against the floor; Fig. 5, a sectional elevation, showing the stretcher as in use, the stretcher-plate and carpet being lifted from the floor; and Fig. 6, a detail.

20 The same letters denote the same parts.

In the drawings, A represents a carpet as being laid upon the floor F, and being stretched in the direction of the arrow in Fig. 5.

B represents what may be termed the "stretcher-plate." In its under side, and toward or at its rear edge, b, it has a series of teeth or points, b', which are inclined or curved forward, as shown, and at or toward its forward edge it has the teeth or points b².

25 C represents a cord attached to the plate B, and leading from the under side thereof.

D represents a crab having the base-plate d, the shaft d' at one end of the base-plate, and teeth or points d² in the under side of the base-plate. A cord, E, leads from the crab-shaft d' and connects with the cord C by means of the hook e.

In practice the plate B is connected with the carpet A by means of the teeth b'. The crab is fixed in front of the plate by inserting 40 the teeth d² in the floor F and holding the end d³ of the base-plate d down, and either by inserting the end d³ under the strip G or by placing the foot upon it, and the cords E and C hooked together. Then by winding the cord 45 E on the crab-shaft the parts are drawn into the position shown in Fig. 5, the carpet being lifted slightly from the floor F and stretched in the desired direction. If the carpet needs a second stretching, the plate B is fixed and 50 the carpet prevented from slipping back by pressing the forward edge of the plate down, so as to fix the points b² in the floor, as shown in Fig. 4. When this is done the crab is moved and readjusted and the stretching operation 55 repeated. The strip G is attached to the wall or wall-board H.

I claim—

1. The combination of the stretcher-plate B, having the teeth b', the cord C, the crab D, and 60 the cord E, substantially as described.

2. The combination of the plate B, teeth b'
b², the cords C E, and the crab D, substan-
tially as described.

3. The combination of the plate B, teeth b'
b², the cords C E, and the crab D, having the
teeth d² and the extended plate d, substan-
tially as described.

Witness my hand.

WILLIAM E. HENDERSON.
